FIG. 2.

Thomas A. Peebles
by Clarence D. Wolcott
Inventor

UNITED STATES PATENT OFFICE.

THOMAS A. PEEBLES, OF PITTSBURGH, PENNSYLVANIA

REGULATION OF COMBUSTION.

Application filed December 18, 1922. Serial No. 607,628.

To all whom it may concern:

Be it known that I, THOMAS A. PEEBLES, residing at Pittsburgh, in the county of Allegheny and State of Pennsylvania, a citizen 5 of the United States, have invented or discovered certain new and useful Improvements in the Regulation of Combustion, of which improvements the following is a specification.

10 Difficulty has been encountered in the operation of automatic mechanism for controlling the combustion in the furnace of boilers in which the flow of products of combustion from the furnace is controlled by the demand on the boiler and the supply of air in accordance with changes in pressure in the combustion chamber. This difficulty is due to a characteristic of the fan most generally used for producing the forced draught. 15 Such characteristic being due to the fact that if when such a fan is operated at a given speed and the pressure against which the air is delivered is increased, the volume of air delivered by the fan will decrease. It 20 is a general practice for all forced draft stokers to so operate the fan that a pressure of 5 or 6 inches (water gauge) is maintained in the conduit leading to the underside of the fuel bed where the demand on the boiler 25 is high. When the demand for steam is comparatively small the stack damper will be opened only a small amount and the damper controlling the flow of air to the fuel bed will be in a corresponding position, reducing 30 the delivery of air to the fuel bed. This reduction in the rate of delivery of the air to the fuel increases, for the reasons above stated, the pressure against which the air is delivered by the fan into a conduit. The 35 demand may be such that it requires an air pressure of only one inch under the fuel bed to compensate for the pressure above the fuel bed, due to the escape of gases from the stack. In such case the air damper will be 40 nearly closed so as to reduce the pressure under the fuel from 7 or 8 inches in the conduit to which it would be increased following the closing of the air damper, to 1 inch. In other words, a condition would be established 45 in which there will be a drop of pressure of 6 or 7 inches across the air damper and a very high velocity of air flowing through a small opening. If now, the demand on the generator be increased slightly, the stack damper would be slightly opened 50 reducing the pressure in the furnace and

this reduction of furnace pressure will cause a shifting of the air damper. The drop of the pressure in the furnace being small, the movement of the air damper will also be 55 small, but on account of the high pressure on the fan side of the air damper, this small opening of the air damper will admit such a volume of air that the pressure above the fuel bed in the furnace will be increased beyond that required to compensate. This increase of pressure will cause an operation of the furnace machine to so close the air damper that there will be a reduction of 60 pressure in the furnace chamber below normal and not due to escape of products of combustion and this back and forth movement of the air damper will continue although there has been no change in the demand on the boiler. 70

The invention described herein has for its object a primary regulation of the supply of air in accordance with the demand on the generator whereby the rate of flow to the conduit will be varied in the same 75 direction as the rate of flow of products of combustion from the furnace and then regulating the flow of air to the under side of the fuel bed, by and in accordance with changes of pressure of gases in the furnace 80 above the fuel bed. The invention is hereinafter more fully described and claimed. 85

In the accompanying drawings forming a part of this specification, Fig. 1 is a diagrammatic view showing the automatic 90 mechanism for controlling the escape of products of combustion from the furnace, the primary and secondary air supply to the furnace and the feeding of fuel; Fig. 2 is a view similar to Fig. 1 illustrating a modification 95 of the construction shown in Fig. 1.

In the practice of the invention a master regulator A is employed, said regulator being operated by and in accordance with changes of the pressure of the steam and preferably of the type and construction shown and described in Letters Patent No. 1,371,243, granted March 15, 1921, to John M. Hopwood. This master regulator is connected by pipe 2 to the outlet pipe 3 of the boiler 100 so that by variation in pressure of steam the mechanism will be operated as described in said patent to shift the frame 4 of the master regulator up and down as the steam pressure increases or diminishes. This frame 4 is connected by a rod 5 and a bell crank lever 6 to an arm 7 on the shaft of

the damper 8 in the outlet stack 9 so that by the operation of this mechanism this damper will be shifted towards opened or closed position as the demand on the boiler 5 changes. This frame 4 is also connected by a chain 10 passing over suitable pulleys to a lever 11, operating a valve mechanism, preferably of the roto-reciprocating type shown and described in Letters Patent No. 10 1,247,217, granted November 20th, 1917, to Brown and Reeser. This valve mechanism controls the flow of steam or other fluid pressure through a pipe 13 to a motor 14 preferably of the turbine type, operating a 15 fan 15, whose outlet is connected to a conduit 16 leading to the underside of the fuel bed of the furnace. In the construction shown in Fig. 1 the frame 4 is also connected by a chain 17 to a lever 18 of a rheostat 19 20 controlling a circuit including the motor 20 for operating the fuel feeding mechanism 21, which may be of any desired type or construction.

A furnace machine B, preferably of the 25 type or construction described and shown in the right in Fig. 3 of the Patent No. 1,338,924, granted May 4, 1920, to John M. Hopwood, is connected by a pipe 22 to the interior of the furnace at a point above the 30 fuel bed. This mechanism is so constructed as described in said Letters Patent, that by variation of pressure in the furnace a piston of the pressure cylinder 23 will be moved up or down in accordance with pressure of the furnace as it decreases or increases, thereby shifting the frame 24, said frame being connected by a rod 25 to an arm 26 on the shaft of the damper 27, in the air conduit 16.

40 In the operation of this apparatus a change of steam pressure, say an increase in demand, will cause such a movement of the frame 4 of the master regulator as to move the stack damper 8 towards open position 45 thereby permitting a freer escape of products of combustion and a consequent reduction of pressure in the furnace of the generator. This movement of the frame 4 will also so operate the lever 11 connected 50 to the movable member of the valve mechanism 12 as to permit freer flow of steam to the motor 14 and a consequent increase of the speed of the fan and of delivery of air into the conduit 16, thereby increasing the 55 pressure of air in the conduit anterior to the damper 27 proportional or approximately proportional to the flow of products of combustion from the stack. On the reduction of pressure in the furnace due to 60 opening of the stack damper 8, the furnace machine B will be operated in such direction as to move toward open position the damper 27, thereby admitting air in greater quantities to the underside of the fuel bed.

65 It will be understood that these mecha-

nisms when installed are so adjusted that under normal conditions the fan will deliver air to the conduit 16 or anterior to the damper 27, at a pressure a little in excess of that desired under the fuel bed under normal conditions of the fuel in the fuel bed, and by the operation of the furnace machine the damper 27 will be shifted to adjust the pressure under the fuel bed to the point required. In other words in this construction of apparatus there is a primary control of the air supplied in accordance with changes in the demand on the generator and a secondary control effected by and in accordance with changes in pressure above the fuel bed. 70 75 80

In the construction shown in Fig. 1 the speed of the fan is varied in accordance with changes in the demand on the generator. In lieu of employing such a fan, having a variable rate of operation, a fan having a constant rate of operation or other suitable means adapted to deliver to the conduit a volume of air slightly in excess of the expected maximum demand is employed, and the reduction of this high pressure to a pressure variable in accordance with changes in demand from time to time on the generator, is effected by means of a damper 28 in the conduit intermediate the source of supply and the master damper 27, said damper being operated by the master regulator A, by means of a rod 29 connecting the frame 4 of the master regulator with an arm 30 on the shaft of the damper 28 as shown in Fig. 2. 85 90 95 100

In the construction shown in Fig. 2 the feed of fuel is controlled by the master regulator, which is operatively connected by an arm 31 to a valve 32 controlling the flow of fluid pressure to the motor 33 from any suitable 105 source.

I claim herein as my invention:

1. The method herein described for regulating the combustion of fuel in a vapor generator which consists in regulating the escape of gases by and in accordance with the demand on the generator, effecting a primary regulation of the air for combustion by and in accordance with the demand on the generator, and effecting a further regulation of the air for combustion, by and in accordance with the pressure of gases above the fuel bed. 110 115 120

2. The method herein described of regulating the combustion of fuel in a vapor generator which consists in providing a supply of air at a pressure required for the operation of the generator at a maximum rating, regulating the flow of air to the underside of the fuel bed by and in accordance with the pressure of gases above the fuel bed, regulating by and in accordance with the demand on the generator the flow of gases from the combustion chamber and the flow of air from the point of supply 125

- to the point where the flow of air to the underside of the fuel bed is regulated.
3. The method herein described of regulating the combustion of fuel in a vapor generator which consists in providing a supply of air at a pressure required for the operation of the generator at a maximum rating, regulating the flow of air to the underside of the fuel bed by and in accordance with the pressure of gases above the fuel bed, regulating by and in accordance with the demand on the generator the flow of gases from the combustion chamber, the flow of air from the point of supply to the point where the flow of air to the underside of the fuel bed is regulated, and the supply of fuel.
4. The method herein described of regulating the combustion of fuel in a vapor generator which consists in regulating the escape of products of combustion and the feed of fuel by and in accordance with the demand on the generator, effecting a primary regulation of the supply of air for combustion by and in accordance with the demand on the generator and effecting a further regulation of the supply of air by and in accordance with the pressure of gases above the fuel bed.
5. The combination of a vapor generator having a furnace, means for controlling the escape of gases from the furnace, means adapted to supply air for combustion at a pressure greater than that required for operating the generator at maximum rating, means operative by and in accordance with changes in the pressure of gases above the fuel bed for regulating the pressure of air under the fuel bed, means operative by and in accordance with the demand on the generator for regulating the pressure of air anterior to the point where flow to the underside of the fuel bed is effected, and means for regulating the means employed for controlling the escape of gases from the furnace by and in accordance with the demand on the generator.
6. The combination of a vapor generator having a furnace, means for supplying fuel, means for controlling the escape of gases from the furnace, means adapted to supply

air for combustion at a pressure required for the operation of the generator at maximum ratings, means operative by and in accordance with changes in pressure above the fuel bed for regulating the pressure of air under the fuel bed, and means operative by and in accordance with the demand on the generator for regulating the supply of fuel, the escape of gases and the pressure of air anterior to the point where the flow to the underside of the fuel bed is regulated.

7. The method herein described of regulating the generation of steam which consists in regulating the escape of gases generated and the combustion of fuel by and in accordance with the pressure of steam, effecting a primary regulation of the air for combustion of the fuel by and in accordance with the pressure of steam and effecting a further regulation of the air for combustion by and in accordance with the pressure of furnace gases.

8. The combination of a vapor generator having a furnace with means operative by and in accordance with the pressure of steam in the generator for regulating the escape of gases from the furnace, means operative by and in accordance with the pressure of steam for effecting a primary regulation of the air for combustion and means operative by and in accordance with the pressure of gases above the fuel bed for effecting a further regulation of the air for combustion.

9. The combination of a vapor generator having a furnace with means operative by and in accordance with the pressure of steam for regulating the escape of products of combustion from the furnace and the feed of fuel to the furnace, means operative by and in accordance with the pressure of steam for effecting a primary regulation of the supply of air for combustion, and means operative by and in accordance with the pressure of gases above the fuel bed for effecting a further regulation of the supply of air for combustion.

In testimony whereof, I have hereunto set my hand.

THOMAS A. PEEBLES.
